GRATE

Ernest Rinfret, Montreal, Quebec, Canada

Application November 13, 1933, Serial No. 698,095
In Canada November 15, 1932

2 Claims. (Cl. 126—171)

The present invention relates to improvements in grates for furnaces and its main object is to provide a grate that will burn soft coal without smoke; reduce ashes to a minimum due to its efficient combustion, and naturally economize in coal consumption. A further object is to make a grate of the "cone-type" that is cheap and simple to manufacture, and one that may be alternately dumped or shaken. Another object is to provide a grate of this character which may be used equally in rectangular or in circular types of furnaces; and another object is to make a grate in which the ashes will not remain and clog in the bottom, as is usually the case in grates of this type.

The invention mainly consists of a grate formed of oblique-side-walls suitably supported within the fire-box of a furnace, so that the air will circulate therearound and through said side-walls, the bottom or central open portion thereof being closed by a dome-like member which is mounted upon a ball-joint so that it may be dumped or simply shaken as the case may be. In large sized furnaces, a movable circumferential grate is provided around said dome-member, said movable grate being adapted to be shaken simultaneously with said dome-member.

In the accompanying drawings:

Fig. 1 is a top view of the grate, part of it being broken away to disclose the structure;

Fig. 2 is a side elevation view of the grate, showing the guideway for shaking and dumping the dome-member;

Fig. 3 is an enlarged vertical section through the dome-member and support therefor;

Fig. 4 is a segmentary top view of the dome-member and movable grate;

Fig. 5 is an enlarged top view of a portion of the circular supporting member upon which the side-walls of the grate are mounted, and

Fig. 6 is an enlarged cross-section through a portion of the side-wall of the grate, the supporting member and movable grate.

Like numerals of reference indicate corresponding parts in each figure.

Referring to the drawings, 1 represents the cross-bars which are secured within the firebox of a furnace (not shown) by means of the standards 2 or any other suitable means and upon which is supported and secured the circular-supporting-member 3. The said supporting-member 3 is preferably provided with a plurality of elongated slots 4, through which may project the bolts 5 adapted to rigidly secure the oblique-side-walls 6 of the grate. The supporting-member 3

as well as the side-walls 6 of the grate should preferably be constructed in sections, as disclosed in the drawings.

When the side-walls 6 are in fixed position, an open space, in the bottom, is provided which is preferably closed by the dome-member 7. The said dome-member may extend to fully fill said open-space or, if desired, may extend over only a portion thereof, so as to leave a circumferential opening, which, in this case is closed by a horizontal and movable-circular-grate member 8, adapted to move horizontally and that may be operated simultaneously with said dome-member 7, as will hereinafter be fully disclosed.

The dome-member which may be in the shape of an integral half ball is preferably supported upon the bracket 9 mounted upon the cross-bars 1, which has a cup-shaped socket 10 in which engages the ball-end 11 of the supporting bracket mounted upon the under-side of said dome-member 7 (see Fig. 3 of the drawings). In so mounting the dome-member 7, it will readily be tilted to dump the combustible, as well as horizontally shaken to remove the ashes accumulated in the grate.

For this purpose, an arm 12 is secured to the side of said dome-member, which extends through a semi-circular opening 13 provided through the side-wall of the grate. The said arm being of rectangular shape will readily be rotated within said circular opening so as to dump the dome-member, but, if it is desired to only shake the said dome-member, the arm 12 is moved laterally to and fro in the horizontal elongated opening 14, that extends from said circular opening 13. The arm 12 being rectangular in shape will prevent it from being rotated, thus avoiding tilting of the dome-member.

The circular grate member 8 is preferably shaken simultaneously with the dome-member 40 by means of a plurality of parallel transverse ribs or projections 15 which are provided upon its surface, said ribs extending to the lower edges of said dome-member and are adapted to engage corresponding slots or depressions 16 located in the inner edge of said circular-grate. When the dome-member is moved or shaken horizontally, the ribs engaging said depressions will accordingly move said circular-grate horizontally, thus causing any ashes that usually accumulate at this point, to fall through the openings 17 provided in said circular-grate.

The transverse ribs located upon the surface of the dome-member will serve also another object, than to actuate the circular grate 8. When

shaking the dome-member these ribs will serve to shake, somewhat like a poker, the combustible within the grate, thus causing all ashes to fall through the grate openings, with the result that 5 the said combustible will be thoroughly cleaned of ashes.

The circular grate 8 is preferably suitably supported by means of the circumferential rail 18 rigidly secured to the circular-supporting-member 3, by means of the radial lugs 19. In Fig. 6 of the drawings, the said rail 18 is disclosed as integral with the supporting member 3 but this is naturally optional. A longitudinal recess 20 is provided in which slidably engages the outer 15 edge of the circular-grate 8 and in which it is suitably seated, the lower end of the side-wall 6 of the grate extending above same, to form a channel or guideway in which it is movably held. The opposite side of said circular grate 8 is supported by the rail 18, which is tapered to reduce 20 friction, and upon which it slides. The rear edge of the said supporting member 3 may be grooved-in or recessed longitudinally at 21 (see Fig. 6 of the drawings), for the purpose of economy in 25 material.

It should be understood that only the essential features of the grate according to the invention are herein described and illustrated in the accompanying drawings, and that modifications 30 may be made without departing from the spirit and scope of the following claims of novelty.

For instance, without departing from the spirit of the invention, by slightly altering the shape of the dome-member as well as the shape of the

circular-grate 8, this improved grate may be used in rectangular furnaces.

What I claim as my invention is:—

1. A grate of the character described, comprising side-walls and a dome-member movably mounted at the bottom thereof between said side-walls, means for shaking said dome-member, said dome-member having a plurality of transverse ribs located upon its surface, a horizontal grate located between the edges of said dome-member and the inner side of said side-walls, said horizontal grate having disposed around its inner edge a plurality of slots in which register the ribs provided upon said dome-member, whereby, when said dome-member is shaken horizontally, said horizontal grate will be simultaneously actuated. 10

2. A grate of the character described comprising side walls, a dome-member movably mounted at the bottom thereof between the side walls and spaced therefrom, means for shaking and dumping said dome-member, a horizontal ring grate movably mounted between the lower edges of the dome-member and the inner side of the side walls of the grate, means to support the horizontal grate and cooperating means carried by 25 the dome-member and ring grate whereby the dome-member and ring grate will be simultaneously shaken and said cooperating means permitting dumping movement of the dome-member independently of the ring grate, said cooperating 30 means including upstanding ribs carried by the dome-member and spaced notches in the inner edge of said ring grate for reception of said ribs.

ERNEST RINFRET.
